(57) **CLAIM**

The ornamental design for a wall block, as shown and described.

DESCRIPTION

FIG. 1 is a perspective view of a wall block, as viewed from the rear, top, and one side showing my new design.

FIG. 2 is a rear elevation view thereof.

FIG. 3 is a front elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a perspective view of the wall block of FIG. 1, as viewed from the rear, bottom, and one side.

The broken lines in the drawings represent unclaimed subject matter and form no part of the claimed design.

1 Claim, 5 Drawing Sheets
